UNITED STATES PATENT OFFICE.

CHARLES MINSHALL, OF TERRE HAUTE, INDIANA, ASSIGNOR TO THE STANDARD WHEEL COMPANY, OF SAME PLACE.

DESIGN FOR A HUB-FLANGE.

SPECIFICATION forming part of Design No. 34,290, dated March 26, 1901.

Application filed December 14, 1900. Serial No. 39,930. Term of patent 7 years.

To all whom it may concern:

Be it known that I, CHARLES MINSHALL, a citizen of the United States, residing at Terre Haute, in the county of Vigo and State of Indiana, have invented and produced a new and original Design for a Hub-Flange; and I do hereby declare the following to be a full, clear, and exact description of the invention, such as will enable others skilled in the art to which it appertains to make and use the same.

Figure 1 is a side elevation, and Fig. 2 is an end view, of a hub-flange embodying my new design.

The larger portion of the flange (shown at the left-hand end of Fig. 1 in dotted lines) is a minor portion of my new design, and its exact configuration therefore is of less importance than the portion shown in full lines, which forms the essential feature of my de-

sign and embraces the cylindrical portion A, 20 provided with parallel rows of pyramidal projections rising above the adjoining portion of the flange. Outside of the portion A is a circumferential groove B, between two narrow beads C C', and beyond the bead C' is a 25 slightly-tapering surface D, having a rounded end d. The portions B, C, C', and D are smooth.

Having thus described my invention, what I claim is—

The design for a hub-flange, substantially as herein shown and described.

In testimony whereof I affix my signature in presence of two witnesses.

CHARLES MINSHALL.
